(57) **CLAIM**

The ornamental design for a sash lock and keeper, as shown and described.

DESCRIPTION

FIG. 1 is a right side view of a sash lock and keeper showing our new design;

FIG. 2 is a left side view thereof;

FIG. 3 is a rear elevational view thereof;

FIG. 4 is a front elevational view thereof;

FIG. 5 is a front, top perspective view thereof;

FIG. 6 is a rear, top perspective view thereof; and,

FIG. 7 is a top plan view thereof.

The broken lines environment is for illustrative purpose only and forms no part of the claimed design.
